SPARK PLUG

Hector Rabezzana, Flint, Mich., assignor to General Motors Corporation, Detroit, Mich., a corporation of Delaware

Application March 27, 1937, Serial No. 133,341

6 Claims. (Cl. 123—169)

My invention relates to spark plugs for internal combustion engines, and particularly to means located adjacent the upper end of the hollow shell or casing of the plug for holding the insulating member thereof in place within the casing. Said holding means is in the nature of a gasket at the upper end of the shell, although perfect gas tightness of the plug is secured for the most part by a yieldable gasket within and adjacent the lower end of the shell.

The holding means comprises a resilient annular metallic member surrounding and resting upon a shoulder provided adjacent the upper end of the insulating member of the plug when it is assembled within the shell and means, which may take various specific forms, for holding said member and the insulating member in place within the hollow shell. Said annular member is curved or C-shaped in cross-section and, being made of a metal such for example as spring steel selected with that end in view, it is resilient and, due to its form as hereinafter appears, acts like an extremely stiff spring against an upper shoulder of the insulating member and forces said member against a suitable gasket which is supported by an internal ledge located adjacent the lower end of the shell.

The drawing submitted herewith illustrates various embodiments of my invention adapted in each case to hold an insulating member in place within the shell or casing of a spark plug; and the particular features wherein my invention consists are enumerated in the claims at the end of this specification.

In the drawing:

Figure 1 is a fragmentary view partly in section showing my invention used to hold the insulating member of a glow plug in place in a passage provided for it.

Figure 2 is a similar view showing my invention used with a spark plug, to hold the insulating member thereof in place within the shell or casing of the plug.

Figure 3 is a view showing the annular metallic resilient holding member of my invention by itself, and upon a larger scale than in Figures 1 and 2.

Figure 4 is a fragmentary view showing an alternative method of securing the annular holding member and the insulating member in place.

Figures 5 and 6 are fragmentary views showing still another method of securing the annular holding member in place within the upper end of the shell of the plug.

Referring to the drawing, the numeral 10 designates the hollow metallic shell or casing of a spark plug, the same having an internal ledge 11 adjacent its lower end which supports the insulating member 12; a suitable gasket 13 or equivalent means for securing a gas tight joint

between the insulating member and the shell being shown between said ledge and a lower shoulder 14 of the insulator. When as shown in Figure 1 my invention is used in connection with a glow plug having a longer insulating member 15 than is ordinarily used in spark plugs, said member is commonly housed within a passage in a cylinder head 16 and is supported by an internal ledge like the ledge 11 against which the insulator is forced by a gland nut 17 in threaded engagement with the upper end of said passage.

The insulating member has an annular shoulder 18 adjacent its upper end; and the numeral 19 designates an annular resilient member C-shaped in cross-section which surrounds the upper part of the insulating member and rests upon said shoulder, and which annular member (in Figure 2) is held in place within the shell by an inturned holding flange 20 at the upper extremity of the shell. This annular C-shaped member is made up of a lower part 191 which engages the shoulder 18, an upper part 192 which is engaged by and lies beneath the holding flange 20 (as in conventional single piece spark plugs), and an intermediate part 193 which is offset toward the axis of the insulating member 12 and is stressed as force is applied to the upper part as the flange 20 is turned inward and forced against said upper part in assembling the plug. It therefore follows that in the finished plug the insulating member is forced against the ledge 11 by the C-shaped member which acts as an extremely stiff spring, which yields during the assembling of the parts, and which in the finished plug acts to force the insulating member toward the ledge 11 and maintain gas tightness thereof when the plug is in use; such gas tightness, as stated, being due for the most part to the intimate joint thus secured between the ledge 11 and the lower shoulder 14 of the insulating member.

In Figure 1 a washer 21 is interposed between the upper extremity of an annular resilient member 22 which acts against an upper shoulder 23 upon the insulating member 15, said washer being held in place by an inturned flange 24 of the gland nut 17. The member 22, however, is similar in action to the member 19 and acts in the same way to force the insulating member 15 against a lower ledge at 25, although in this embodiment of my invention the resilient member 22 is subjected to pressure by screwing the gland nut 17 into the upper end of the passage provided for the insulating member 15, rather than during a turning inward operation whereby the flange 24 is formed. In both forms, however, the insulating member of the plug is held in place and forced against a lower or inner supporting ledge by a resilient member of C-shape cross-section, which acts as a stiff spring to hold

the insulator in place and maintain a gas tight joint at the lower or inner end of the plug.

The insulating member and the resilient C-shaped member may be held in place within the shell of the plug by a gland nut, as in conventional plugs not of the single piece type. Thus Figure 4 shows the insulator 26 as having an upper shoulder 27 against which an annular resilient member 28 acts precisely as in the forms 10 of my invention illustrated in Figures 1 and 2, but in this form pressure to compress said member and bring about its resilient holding function is produced by screwing a gland nut 29 into the upper end of the passage within the shell 30 15 provided for the insulating member.

The periphery of the lower end 191 of the resilient C-shaped member (see Figure 2) is spaced slightly away from the interior of the passage in the shell provided for it and the 20 insulating member, as at 31, so that said lower end may adapt itself to the upper shoulder of the insulating member during the assembling of the parts without binding, as might be the case if the periphery of said lower end came into contact with the interior of said passage during the 25 assembling of the parts. Such spacing, moreover, results in a more free and unrestrained action of said member as a spring as its lower end is, to a degree, free to move sidewise as it is subjected to axial compression during the assembling of the parts within the hollow shell or casing 30 of the plug.

As an alternative method of securing the C-shaped annular resilient member in place within the hollow shell of the plug I may, as shown 35 in Figures 5 and 6, form an internal groove 32 in the inner cylindrical wall of the shell 33, which must obviously be initially large enough in diameter to receive the insulating member 34 and 40 the resilient member 35 which as hereinbefore engages with an annular shoulder 36 adjacent the upper end of the insulating member; the upper end of the member 35 occupying a position slightly above the groove, as shown, when the 45 parts are placed loosely within the shell and before said member is compressed and permanently fastened in place within the upper end of the shell.

The resilient member is next forced downward 50 as by a suitable press having a hollow plunger or ram, thus forcing the lower shoulder of the insulating member against a ledge within the casing and the lower end of the resilient member 35 into firm engagement with the upper shoulder 36, and setting up a force in said member which tends to elongate it, and which force 55 acts resiliently throughout the life of the plug to always force the insulating member toward the inner annular supporting ledge adjacent the lower end of the shell.

Then and while the parts are held with the upper end of the C-shaped member 35 down and opposite the groove 32 the upper end of the shell 33 is constricted and forced inward, as by a 60 plunger or ram having a conical recess in its lower end, during which step the periphery of the upper end of the C-shaped member 35 enters the groove 32 thus locking said member in place under compression as will be understood from 65 Figure 6 of the drawing.

Having thus described and explained my invention, I claim and desire to secure by Letters Patent:

1. In a spark plug and in combination with an 75 insulating member having an annular shoulder

adjacent its upper end; an annular metallic resilient member C-shaped in cross-section surrounding said insulating member and resting upon said shoulder, and which member comprises lower and upper parts spaced apart from one another and an intermediate part offset toward the axis of said insulating member; and means engaging the upper end of said resilient member for holding it and said insulating member in place within a suitable shell or casing.

2. In a spark plug, a hollow shell; an insulating member supported within said shell, and which member has an annular shoulder adjacent its upper end; an annular metallic resilient member C-shaped in cross-section surrounding said insulating member and resting upon said shoulder, and located within the upper end of said shell, and which member comprises lower and upper parts spaced apart from one another and an intermediate part offset toward the axis of said insulating member; and means engaging the upper end of said resilient member for holding it and said insulating member in place within said shell.

3. In a spark plug, a hollow shell; an insulating member supported within said shell, and which member has an annular shoulder adjacent its upper end; an annular metallic resilient member C-shaped in cross-section surrounding said insulating member and resting upon said shoulder, and located within the upper end of said shell, and which member comprises lower and upper parts spaced apart from one another and an intermediate part offset toward the axis of said insulating member; and an inturned flange at 35 the upper end of said shell and engaging the upper end of said resilient member for holding it and said insulating member in place within said shell.

4. In a spark plug, a hollow shell having an internal ledge adjacent its lower end; an insulating member within said shell and supported by said ledge, and which member has an annular shoulder adjacent its upper end; an annular metallic resilient member C-shaped in cross-section 45 surrounding said insulating member and resting upon said shoulder, and located within the upper end of said shell, and which member comprises lower and upper parts spaced apart from one another and an intermediate part offset toward the axis of said insulating member; and an inturned flange at the upper end of said shell and overlying the upper end of said resilient member for holding it and said insulating member in place within said shell.

5. In a spark plug, a hollow shell having an internal groove adjacent its upper end; an insulating member supported within said shell, and which member has an annular shoulder adjacent its upper end; and an annular metallic resilient member C-shaped in cross-section surrounding said insulating member and resting upon said shoulder, and the upper end of which resilient member lies within said groove.

6. In a spark plug, a hollow shell having an internal ledge adjacent its lower end, and an internal groove adjacent its upper end; an insulating member within said shell and supported by said ledge, and which member has an annular shoulder adjacent its upper end; and an annular metallic resilient member C-shaped in cross-section 70 surrounding said insulating member and resting upon said shoulder, and the upper end of which resilient member lies within said groove.

HECTOR RABEZZANA.
